[57] **CLAIM**

The ornamental design for a draftsman's organizer, as shown and described.

DESCRIPTION

FIG. 1 is a top front and left side perspective view of a draftsman's organizer showing my new design, with parts not shown for ease of illustration.

FIG. 2 is a rear elevational view thereof.

FIG. 3 is a top plan view thereof.

FIG. 4 is a front elevational view thereof, the broken lines showing a bracket and table mounting clamp are shown for illustrative purposes only.

FIG. 5 is a right side elevational view thereof, the left side being a mirror image thereof; and

FIG. 6 is a bottom plan view thereof.
